(57) **CLAIM**

The ornamental design for a multi-bag holding loop as shown and described.

DESCRIPTION

FIG. 1 is a perspective view of the multi-bag holding loop;

FIG. 2 is a front view thereof;

FIG. 3 is a right-side view thereof;

FIG. 4 is a left-side view thereof;

FIG. 5 is a top view thereof; and,

FIG. 6 is a bottom view thereof.

Any broken lines in the drawings are for illustrative purposes of the multi-bag holding loop, depict unclaimed portions and form no part of the claimed design.
